BOTTOM HOLE GAS BEAN

Marcus W. Haines, Long Beach, Calif., assignor
of one-half to Technicraft Engineering Corp.,
Los Angeles, Calif., a corporation

Application October 3, 1934, Serial No. 746,675

9 Claims. (Cl. 166—2)

The present invention is an improved bottom-hole gas bean and relates to an oil well flow device.

The primary object of the invention is the provision of a device for suspension from the lower end of a tubing string, which, when submersed in gas-laden oil, can be used to close the bottom end of the string until the device reaches a level in a well which operation is to be conducted and which carries means for opening and closing ports through which fluid can enter the string.

The invention contemplates means, operable from the mouth of the well and by rotation of the tubing string for regulating the gas-oil ratio of a producing well and thereby conserving the gas, natural to the formation, for its full utilization in lifting oil to the surface.

In the accompanying drawing, Figure 1 is a view, half in elevation and half in section, of a typical form of my device.

Figure 2 is a transverse section of a tube section having ports in its wall, the section being indicated by the dotted line II—II of Figure 1, and Figure 3 is a transverse section of Figure 1 taken on the line III—III of said figure.

Referring to the drawing, the numeral 1 indicates a section of tubing string from which my device is suspended.

Threaded at 2 to the tubing 1 is a tube section 3, threaded at the end remote from member 1, as at 4, for engagement with a closure or cap 6. The tube 3 is provided with ports, slots, or apertures 7, here shown as four in number and spaced in equi-distant relation, as shown in Figure 2.

Tube 3 is threaded exteriorly at 8 for engagement with an internally threaded sleeve member 9 and clearance is provided at 11 so that sleeve 9 can be moved upwardly on said threads to diminish the capacity of the ports 7 by covering a portion thereof.

Integral with, or secured to, tube 3 is an annular flange 12, the lower surface of which is ground to a taper, as indicated at 13, corresponding to a ground seat 14 in a hard-face ring 16 secured to the upper end of tube 3. Flange 12 serves as a stop, limiting the upward movement of sleeve 9, and the ground confronting surfaces 13 and 14 form a valve making the tube 3 fluid tight when said sleeve is threaded to upper, or closed, position indicated in dotted lines in Figure 1.

The lower end of sleeve 9 carries a gasket 17, of rubber or suitable expansive material, which, when compressed between the end of tube 3 and a metal ring 18, expands against the wall of said tube to exclude sand from the threads 8. Screws

19, threaded into sleeve 9 and provided with clearance through ring 18 and gasket 17, effect said compression.

In order to hold tube 3 against rotation when the tubing string 1 is rotated to move the sleeve 5 up or down on said sleeve, I provide bow springs 21, anchored by screws 22 to sleeve 9, and by screws 23 to a collar 24 which is slidable on tube 3.

Operation

My device is secured to the lower end of an open tubing string and closed at the bottom by cap 6.

The string is lowered into the well to a point where the density of the oil makes production possible with a minimum depletion of gas.

It is a well-known fact that fluid in the upper levels in an oil column is frothy and of a lighter gravity than that below.

My device can be lowered from time to time as well pressure subsides and the ports 7 can be regulated in capacity by rotation of the tubing string 1.

The bow springs 21 frictionally engage the inner walls of a surrounding casing and hold the sleeve 9 against rotation. Rotation of the tubing string 1 causes said sleeve 9 to lift and descend, relatively to tube 3, by reason of the threads 8.

This relative movement determines the capacity of ports 7, and the regulation of said ports and selection of the level affording the proper density of oil provide a means for determining the proper gas-oil ratio best adapted to production and to the characteristics of the well wherein the device is employed.

The confronting surfaces of tube 3 and sleeve 9 are ground to a close fit to prevent sand from entering threads 8.

The ports 7 are diametrically opposed so that the force of fluid entering one of said ports will be nullified by that of fluid entering through the opposite port. This is an advantageous feature which prevents sand-cutting.

All valves and inlet openings in flow devices of the character described are subjected to the equivalent of a sand blast when oil containing sand enters at high velocity.

By arranging the ports as described and making them of uniform capacity, this destructive force is eliminated.

I claim:

1. A device of the character disclosed comprising; a tube section including radially directed ports in its sidewalls and means at its upper end for attachment to a tubing string; a sleeve en-

- 5 circling said tube adapted when moved axially with respect to said tube section to open or close the ports in said tube; and means including complementary configurations on the confronting surfaces of said sleeve and said tube for imparting axial movement of said sleeve relative to said tube when the tubing string to which said tube is attached is rotated.
- 10 2. A device of the character disclosed comprising; a tube section including radially directed ports in its sidewalls and means at its upper end for attachment to a tubing string, a sleeve, encircling said tube adapted when moved axially to open or close the ports in said tube, means for anchoring said sleeve against rotation when said tube is rotated; and means for causing axial movement of said sleeve upon rotating said tube relative thereto.
- 15 3. The combination with a well casing and a tubing string within said casing; of a tube section connected to said string and having ports in its side walls; a sleeve surrounding said tube section and arranged to cover said ports; and interengaging means on said tube and said sleeve for moving said members relatively to open and close said ports.
- 20 4. The combination with a well casing and a tubing string within said casing; of a valve body connected to said string and provided with ports through its wall communicating with the interior of the tubing string above the lower end of said valve body; a sleeve valve surrounding said valve body and bow spring means carried by said sleeve valve and coacting with the surrounding casing, for anchoring said sleeve valve against rotation when said tubing string is rotated; and an arrangement for causing said sleeve valve to cover and control said ports in response to rotation of the tubing string.
- 25 40 5. In a bottom hole gas bean, the combination with a tubing string; of a valve body in the form of a tube section depending from the tubing string, said valve body including radially directed ports in its side walls near its upper end, and an annular valve seat externally of the valve body and beyond the one extremities of said ports; a sleeve fitting said valve body and adapted to cover and control the effective area of said ports, said sleeve including an annular valve element adapted when said sleeve has covered said ports to coact with said valve seat to seal said ports.
- 45 55 6. In a bottom hole gas bean, the combination with a tubing string; of a tubular valve body including vertically extending inlet ports above its lower end and adapted to admit well fluid into the valve body and tubing string thereabove, said ports being diametrically disposed and tending to form nozzle elements whereby the streams of fluid entering therethrough impinge against
- each other to minimize wear otherwise caused by abrasive particles suspended in the fluid; and annular valve means surrounding the valve body and adapted to regulate and close said ports; said valve means including a valve element secured to the valve body and turnable therewith, a sleeve carrying a coacting valve element and screwthreadedly mounted on said valve body, and means for restraining said sleeve from rotation whereby rotation of the tubing string and valve body causes axial movement of the sleeve.
- 5 10 15 7. In a bottom hole gas bean, the combination with a tubing string; of a valve body in the form of a tube section depending from the tubing string, said valve body including radially directed ports in its side walls near its upper end, and an annular valve seat externally of the valve body and the one extremities of said ports; a sleeve fitting said valve body and adapted to cover said ports, said sleeve including an annular valve element adapted to coact with said valve seat to seal said ports; means for anchoring the sleeve against rotation when the tubing string and valve body are rotated; and means for causing axial movement of the sleeve upon rotating said tubing string and body member to regulate and close said ports.
- 20 25 8. In a bottom hole gas bean: a pair of tubular members screwthreaded one into the other; means associated with one of said tubular members engageable with the walls of a well bore and tending to restrain its associated tubular member against rotation; a tubing string connected with the other tubular member and adapted to rotate the same whereby said tubing members may be moved axially with respect to each other; and a plurality of ports in the side walls of one tubular member, the other tubular member having a portion moveable past said ports to control the effective area thereof.
- 30 35 40 9. In a bottom hole gas bean: a pair of tubular members screwthreaded one into the other; means associated with one of said tubular members engageable with the walls of a well bore and tending to restrain its associated tubular member against rotation; a tubing string connected with the other tubular member and adapted to rotate the same whereby said tubing members may be moved axially with respect to each other; a plurality of ports in the side walls of one tubular member, the other tubular member having a portion movable past said ports to control the effective area thereof; and a pair of coacting valve elements for said tubular members, said valve elements being axially engageable to seal said ports upon closing of said ports by the port controlling tubular member.

MARCUS W. HAINES.
